UNITED STATES PATENT OFFICE.

HENRY C. CARTER, OF MONTCLAIR, NEW JERSEY.

WASH-BOARD.

SPECIFICATION forming part of Letters Patent No. 313,653, dated March 10, 1885.

Application filed April 5, 1884. (Model)

To all whom it may concern:

Be it known that I, HENRY C. CARTER, of Montclair, in the county of Essex and State of New Jersey, have invented certain new and useful Improvements in Wash-Boards, of which the following is a full, clear, and exact description.

This invention relates to wash-boards fitted with protectors that not only guard against the splashing of the suds up or on to the person of the operator, but also form a broad bearing-surface or rest for the body of the washer-woman or operator when stooping or leaning to the work, and it more particularly refers to that class of wash-board protectors in which the protector is attached to the wash-board by means of slots and pins. The invention is also more particularly designed for use on reversible wash-boards—that is, wash-boards having corrugated zinc or metal rubbing-surfaces on their opposite sides or faces.

My invention consists in a spring-connection of the protector with the wash-board, substantially as hereinafter described, and where-
25 by said protector may not only be readily attached to or detached from the board, as re-
quired, but the arms of the protector, by their elasticity, serve to securely hold the protector in position when in use; and it also consists
30 in a combination of such detachable protector with a double or reversible wash-board, where-
by the same protector may be used on either or both sides, alternately, of the board.

Reference is to be had to the accompanying
35 drawings, forming a part of this specification, in which similar letters of reference indicate corresponding parts in both the figures.

Figure 1 represents a view in perspective of a double or reversible wash-board with my in-
40 vention applied; Fig. 2, a vertical longitudinal section of the same, also showing by dotted lines the protector and one of its spring-
arms detached.

A A are the legs of the wash-board, mounted
45 with the usual cross-head piece or partial body-
support and guard C; and D D are upper and
lower cross-frame pieces, to which the corrugated
zinc or metal plates E E of the double
or reversible board are secured.

50 The protector is composed of a head or cross
piece, G, having spring side arms, H H, of a
slotted form or construction, and each of which

is composed of an elastic bent-wire loop con-
nected at its free ends in a transverse direc-
tion to the protector-board or cross-piece G, 55
which is fitted to engage by an under-groove
construction of its one edge, as at b, with either
upper edge of the guard C, having correspond-
ing grooves, c c.

Projecting from the inner sides of the legs 60
A A, on both or opposite sides of the head-
board B, are hooks or suitably-shaped studs
d d', with which the looped ends of the elas-
tic arms H H of the protector engage. The
distance apart of the elastic arms H H is such 65
that, in order to engage them with or diseng-
age them from the hooks or studs d or d', said
arms require to be pressed toward each other
in order that said hooks or studs may pass
into or out of the slots or openings in the spring- 70
arms, which provides for their retaining their
proper position when in place, and for quickly
detaching the protector, when required, as also
for readily changing the protector from one
side to the other of the double or reversible 75
wash-board.

To change the protector from one side of the
wash-board to the other, first disengage the
cross-piece G from the guard C; then press the
arms H toward each other until they are free 80
of the hooks, when the protector may be ap-
plied to the opposite hooks by first pressing
the arms H toward each other and allowing
them to spring into engagement with the hooks,
and then pressing the cross-piece upward and 85
partially over the edge of the guard C, as shown.
The arms H will then exert a downward press-
ure on the cross-piece G, to hold it firmly to
the guard C.

Furthermore, the two side portions of each 90
elastic wire arm H are so curved or bent apart
in direction of their length, and the hooks or
studs d or d' placed at such distance below the
guard C, that when the protector, which swings
by its arms on said studs, is adjusted into work- 95
ing position and so that its cross-head piece
G engages by its grooved edge with either
grooved edge of the guard C, the spring-arms
H H will be more or less straightened or
stretched, to hold the protector in its engaged 100
position with the cross-head piece C.

Having thus described my invention, I claim
as new and desire to secure by Letters Patent—

1. A removable protector for wash-boards,

consisting, essentially, of a cross-piece provided with two depending slotted or open spring-arms, substantially as set forth.

2. In a removable protector for wash-boards, 5 a cross-piece provided with two open or slotted spring-arms, said arms being formed with bends to cause said arms to exert a pulling-strain when under tension, substantially as set forth.

10 3. The combination, with a reversible wash-board provided with hooks or studs $d d'$, below its guard C, of a removable protector having the cross-piece G, provided with slotted or open spring-arms adapted to spring into 15 engagement with said hooks and to be removed therefrom, substantially as set forth.

4. The combination, with a reversible wash-board provided with hooks or studs $d d'$, below the guard C, of a removable protector consisting of the cross-piece G, having open or 20 slotted spring-arms H, the members of said

spring-arms being bent toward each other, as shown, whereby when the arms engage the hooks d or d' and one longitudinal edge of the cross-piece G overlaps one longitudinal edge 25 of the guard C, a downward pressure will be exerted by said arms to hold said cross-piece to the guard, as set forth.

5. In a reversible wash-board, the combination, with the guard C, grooved at $c c$, and 30 the sides A, provided with hooks $d d'$ on opposite sides, of the cross-piece G, grooved at b to fit one of the grooves c , and the bent slotted spring-arms H, secured to said cross-piece G, and adapted to engage the hooks d or d' , 35 and hold the grooved edges of cross-piece G and guard C in contact to present an unbroken surface, as set forth.

HENRY C. CARTER.
